UNITED STATES PATENT OFFICE

2,433,349

APPARATUS FOR MECHANICALLY OPERATING KEYBOARDS OF TYPEWRITERS AND THE LIKE

William Burnett DREWELL, Croydon, England, assignor to Creed and Company Limited, Croydon, England, a British company

Application February 8, 1945, Serial No. 576,799
In Great Britain February 3, 1944

7 Claims. (Cl. 197—19)

1

This invention relates to apparatus for mechanically operating keyboards of typewriters or the like.

The testing of machines such as typewriters or keyboard-controlled telegraph transmitters must involve means whereby the keyboard may be operated. When large numbers of machines are to be tested, it becomes a lengthy and expensive matter to operate keyboards manually.

It is therefore the object of the invention to provide automatic means whereby a keyboard may be operated.

It is a further object of the invention to provide means whereby all the keys on a keyboard may be operated in any desired sequence which sequence may be changed when desired.

According to the present invention I provide apparatus for mechanically operating the keyboard of a typewriter or the like comprising actuating members for the respective keys, means for supporting the said actuating members above the keys of the keyboard, means for reciprocating the said actuating members towards and away from the keyboard, and means for allowing a selected actuating member only to actuate its corresponding key.

Preferably the means for allowing a selected actuating member only to actuate its corresponding key comprises a set of combination bars arranged transversely of the actuating members and means for positioning said combination bars to present a series of aligned notches to one of said actuating members and an arresting surface to all others.

An embodiment of the invention provided with means for allowing all of said actuating members to be operative in a desired sequence will be described with reference to the accompanying drawings in which:

Fig. 1 is a plan view.

Fig. 2 is a front view.

Fig. 3 is a section on the line 3—3 of Fig. 2 looking in the direction of the arrows.

Fig. 4 is a section on the line 4—4 of Fig. 1 looking in the direction of the arrows.

Figs. 5 and 6 are side views looking in the directions of the arrows 5 and 6 of Fig. 4.

Fig. 7 is a section on the line 7—7 of Fig. 4.

Fig. 8 is a view of the cam shaft;

Fig. 9 is a section on the line 9—9 of Fig. 1.

Fig. 10 is a side view looking in the direction of the arrow 10 of Fig. 1.

Referring to the drawings, the apparatus is

2

provided with a plurality of key actuating buttons 11, one for each key of the keyboard to be tested. Each button 11 is supported on the end of the horizontal arm of inverted L-shaped slideable members 12, the apparatus being such and the horizontal arms of members 12 of such length that a keyboard to be tested may be placed under these arms so that the buttons 11 are over the corresponding keys. The vertical arm of each member 12 is formed with a projection 13, Fig. 9, and a common bail 14 lying under these projections support the members 12 in the positions shown against the pull of individual springs 15. The bail 14 supports the members 12 in such position that the latter lie over but out of contact with combination bars 16 which are slideable longitudinally in comb guides 17 and are formed with notches in a manner well known in the printing telegraph art. The combination bars 16 may be moved to the right in Figs. 1 and 2 (to the left in Fig. 4) by means of a common returning lever 18. Springs 19 are attached to the combination bars and to one of the comb guides 17 whilst springs 20 are contained in grooves in a block 21 and act on fingers 22, which tend to push the combination bars to the right in Fig. 4 and to the left in Figs. 1 and 2. The number of combination bars 16 is dependent upon the number of keys on the keyboard to be tested. Five of such bars are shown, which is sufficient for testing a keyboard having up to thirty-two keys.

In order to move the combination bars lengthwise to present a series of aligned notches to the horizontal portion of one of the members 12 a drum 23 is mounted near to one end of the bars 16 and carries on its periphery a series of wards 24. When the common returning lever 18 is moved, as will be explained hereinafter, the combination bars 16 are moved away from the wards 24 and when the returning lever 18 is restored to the position shown in the drawing, springs 19 and 20 set them against the surface of a ward 24. Each ward is provided with notches to select certain of the bars 16 for further movement than the others and those bars 16 which are opposite a notch in the ward presented to them will be moved further, those bars 16 that are opposite an uncut portion of a ward being moved only slightly. Thus for each ward 24 on the drum 23 the combination bars 16 will be set in a corresponding manner to present a series of aligned notches to one particular member 12.

The movements of the bail 14 and the com-

mon returning lever 18 and the rotation of the drum 23 are controlled by cams 25, 26 and 27 respectively mounted upon a cam shaft 28. Cam shaft 28 is driven from a motor 29 through gearing 30, 31. Cam 26 first acts on bell crank lever 32 to rotate retaining lever 18 about its pivot 33 and so draw all the combination bars 16 away from the ward 24 on the drum 23 with which they are in contact. Whilst these combination bars are so withdrawn the drum 23 is rotated through one step to bring a fresh ward 24 into place to position the combination bars anew. This stepping movement of the drum 23 is effected by the action of cam 27 on a bell crank lever 34 which in turn operates a feed lever 35 (Fig. 4). Feed lever 35 is urged by a spring 36 in such direction as to press bell crank lever 34 against the cam 27. Feed lever 35 carries pivoted thereon a pawl 37 held by a spring 38 in engagement with a ratchet wheel 39 integral with or fastened to drum 23. The feed pawl 37 co-operates with a fixed stop 40 to prevent overshoot of the drum at the end of the feeding motion. A retaining pawl 41 is provided to engage a second ratchet wheel 39 at the opposite side of the drum and prevent backwards rotation of the drum.

Cams 25 of which there are two, act upon the arms 42 of a frame pivoted in brackets 43 and to which bail 14 is fixed, immediately after combination bars 16 have been set, to lower bail 14 and thus allow springs 15 to move members 12 downwards until they rest across the upper surface of combination bars 16. One of these members 12 will find below it a series of aligned notches in the combination bars, permitting it to be drawn downwards sufficiently to cause the button 11, carried thereby, to operate the corresponding key of the keyboard beneath it. The bail 14 is then raised raising the selected member 12 out of the aligned notches in the combination bars and then raising all the members 12 clear of the combination bars.

Thus, at each revolution of the shaft 28 the combination bars are reset by a ward 24 on drum 23 and a particular key actuated. The wards 24 are mounted in the drum 23 in such a manner that they may be readily interchanged and by placing wards 24 in the drum in a desired order all the keys of the keyboard under test may be operated in any required sequence. Alternatively by placing only a limited number of kinds of ward 24 in the drum 23, a given key or a limited number of keys may be operated any desired number of times.

The spindle of the drum 23 is fitted with a barrel cam 44 (Fig. 10) which operates a lever 45 so as to cause it to act once per revolution of the drum spindle to trip a revolution counter 46.

In order to ensure the apparatus being in proper position to commence the testing of a keyboard, a disc 47 is provided on one end of the cam shaft 28 and is marked with a spot 48. That the apparatus is in correct position to be associated with a keyboard is indicated by the appearance of this distinctive spot through an aperture in the instrument cover. In order to turn the cam shaft into such position before placing a keyboard beneath the buttons 11 and connecting a power supply to the motor 29 a hand wheel 49 is provided, fixed to a stub shaft 50 which is mounted in alignment with the shaft of motor 29 but is normally held out of engagement therewith by the action of a compression spring 51. The stub shaft 50 may be pushed into engagement with the

shaft of motor 29, which it engages through a unidirectional dog type clutch 52.

In order to vary the tension exerted by springs 15 on the actuating members 12, the springs 15 are anchored to a plate 53 to which is fastened a guided block 54. Fixed to the block 54 is a traveller nut 55 which is capable of movement up and down a screwed shaft 56. A gear wheel 57 fixed on the shaft 56 meshes with a gear 58 on a shaft 59 extending to the rear of the apparatus where a handwheel 60 is fixed thereto. By rotating the handwheel 60 in one direction or the other the tension of the springs 15 may thus be increased or decreased.

15 Indication of the amount of tension employed is given by a pointer 61 capable of movement up and down and operated on by one end of a lever 62, centrally pivoted, the other end of which is carried by the traveller nut 55.

20 It is clear that the wards 24 and drum 23 may be replaced by other means of setting the combination bars. Various forms of devices for this general purpose have been known heretofore—for example, punched tape controlled devices.

25 What is claimed is:

1. Apparatus for mechanically operating the keyboard of a typewriter or the like comprising slidable key lever actuating members each provided with an arm extending to the key button 30 of the key lever to be actuated and ending in an actuating button facing said key button, common supporting means for said actuating members, mechanically controlled selecting means for selecting any of said actuating members for operation, yielding means for operating a selected actuating member, means for releasing said supporting means upon the setting of said selecting means to permit the operation of said yielding means to move the selected actuating member to actuate the corresponding key lever, and controlling means for said supporting means to overcome the yielding means to move the actuating members into inoperative position.

2. Apparatus for mechanically operating the keyboard of a typewriter or the like comprising slidable key lever actuating members each provided with an arm extending to the key button of the key lever to be actuated and ending in an actuating button facing said key button, common supporting means for said actuating members, mechanically controlled selecting means for selecting any of said actuating members for operation, the said selecting means comprising a set of combination bars arranged transversely of said actuating members and provided with notches and means for positioning said combination bars to present a series of aligned notches to one of said actuating members and an arresting surface to all others of said actuating members, yielding 50 means for operating a selected actuating member, means for releasing said supporting means upon the setting of said selecting means to permit the operation of said yielding means to move the selected actuating member to actuate the corresponding key lever, and controlling means for said supporting means to overcome the yielding means to move the actuating members into inoperative position.

3. Apparatus for mechanically operating the 70 keyboard of a typewriter or the like comprising slidable key lever actuating members each provided with an arm extending to the key button of the key lever to be actuated and ending in an actuating button facing said key button, common supporting means for said actuating mem-

bers, mechanically controlled selecting means for selecting any of said actuating members for operation, the said selecting means comprising a set of combination bars arranged transversely of said actuating members and provided with notches and means to position said combination bars to present a series of aligned notches to one of said actuating members and an arresting surface to all others of said actuating members, said positioning means comprising a step-by-step operated drum provided with wards, means to move said combination bars towards and from said drum including spring means urging said bars towards said drum, yielding means for operating a selected actuating member, means for releasing said supporting means upon the setting of said selecting means to permit the operation of said yielding means to move the selected actuating member to actuate the corresponding key lever, and controlling means for said supporting means to overcome the yielding means to move the actuating members into inoperative position.

4. Apparatus for mechanically operating the keyboard of a typewriter or the like comprising slidable key lever actuating members each provided with an arm extending to the key button of the key lever to be actuated and ending in an actuating button facing said key button, common supporting means for said actuating members, mechanically controlled selecting means for selecting any of said actuating members for operation, the said selecting means comprising a set of combination bars arranged transversely of said actuating members and provided with notches and means to position said combination bars to present a series of aligned notches to one of said actuating members and an arresting surface to all others of said actuating members, springs urging said combination bars into engagement with the positioning means, means to withdraw said combination bars from the positioning means and to release said combination bars after the positioning means has been set for a fresh selection, yielding means for operating a selected actuating member, means for releasing said supporting means upon the setting of said selecting means to permit the operation of said yielding means to move the selected actuating member to actuate the corresponding key lever, and controlling means for said supporting means to overcome the yielding means to move the actuating members into inoperative position.

5. Apparatus for mechanically operating the keyboard of a typewriter or the like comprising slidable key lever actuating members each provided with an arm extending to the key button of the key lever to be actuated and ending in an actuating button facing said key button, common supporting means for said actuating members, mechanically controlled selecting means for selecting any of said actuating members for operation, yielding means for operating a selected actuating member comprising a plurality of springs adjustable as to tension by means comprising a movable anchor plate to which one end of each spring is fastened, a traveler nut fixed to said anchor plate, a screw shaft cooperating with said traveler nut, a hand wheel at the exterior of the apparatus, and gearing means operable by said hand wheel to operate said screw shaft, means for releasing said supporting means upon the setting of said selecting means to permit the operation of said yielding means to move the selected actuating member to actuate the corre-

sponding key lever, and controlling means for said supporting means to overcome the yielding means to move the actuating members into inoperative position.

- 5 6. Apparatus for mechanically operating the keyboard of a typewriter or the like comprising slidable key lever actuating members each provided with an arm extending to the key button to be actuated by the said actuating member and ending in an actuating button facing the said key button, a yielding means for each actuating member tending to urge it into operative position, a common bail for said actuating members for retaining said members in the inoperative position, a set of combination bars arranged transversely of said actuating members and provided with notches, a recessed step-by-step operated pattern device for engagement with said combination bars to set the same, springs arranged to urge the combination bars towards the said pattern device to effect the setting of said combination bars, means for releasing the said bail after the setting of the combination bars to permit the movement of said actuating members towards the notched surfaces of the combination bars and the dropping into a series of aligned notches of the actuating member corresponding to the particular setting of the combination bars, thus permitting the yielding means to actuate the corresponding key lever by means of the said actuating member and the actuating button, means for withdrawing after the actuation of a key lever all of said actuating members by means of said bail into inoperative position, and means effective after such withdrawal to advance the said pattern device by one step for another selection.

- 40 7. Apparatus for mechanically operating the keyboard of a typewriter or the like comprising 40 slidable key lever actuating members each provided with an arm extending to the key button of the key lever to be actuated and ending in an actuating button facing said key button, common supporting means for said actuating members, mechanically controlled selecting means for selecting any of said actuating members for operation, the said selecting means comprising a set of combination bars arranged transversely of said actuating members and provided with notches and means to position said combination bars to present a series of aligned notches to one of said actuating members and an arresting surface to all others of said actuating members, said positioning means comprising a step-by-step operated drum provided with interchangeable code wards for obtaining different required cycles of operation of the key actuating members and means to move said combination bars towards and from said drum including spring means urging said bars towards said drum, yielding means for operating a selected actuating member, means for releasing said supporting means upon the setting of said selecting means to permit the operation of said yielding means to move the selected actuating member to actuate the corresponding key lever, and controlling means for said supporting means to overcome the yielding means to move the actuating members into inoperative position.
